G. POSNICK,
SHAVING GAUGE,
FILED NOV. 28, 1921.

George Posnick. INVENTOR.

BY

Harry W. Brown. ATTORNEY.

UNITED STATES PATENT OFFICE.

GEORGE POSNICK, OF SPRINGFIELD, MASSACHUSETTS.

SHAVING GAUGE.

Application filed November 28, 1921. Serial No. 518,223.

To all whom it may concern:

Be it known that I, GEORGE POSNICK, a citizen of the United States of America, residing at Springfield, in the county of 5 Hampden and State of Massachusetts, have invented certain new and useful Improvements in Shaving Gauges, of which the following is a specification.

This invention relates to improvements in 10 shaving gauges.

The object of the invention is to provide a device which is designed to be attached to a safety razor, whereby the cutting edge is accurately positioned when the razor is 15 used. It is not designed to be used with any particular make of razor and the razor shown in the drawings is merely illustrative.

The invention broadly considered comprises a member adapted to be attached to 20 the razor, a part for engaging the upper side and back portion of the ear close to the head, and another part for engaging the eyebrow, whereby the cutting edge of the razor is positioned each time it is used.

25 Means are provided for varying the position of the cutting edge of the razor, that is to say, the point at which the razor commences to trim the hair may be varied as desired. This will be clearly understood from 30 the detailed description.

Referring to the drawings:

Fig. 1 is a side elevational view showing the device as used.

Fig. 2 is a plan view in which the position 35 of the parts of the device are reversed from that shown in Fig. 1.

Fig. 3 is a view similar to Fig. 2 with the part that engages the eyebrow folded, and the telescoping tube moved inward on to 40 the main rod.

Fig. 4 is a view on the line 4-4 of Fig. 3 illustrating the pivotal connection of the part by means of which the device is clamped to the razor, and

45 Fig. 5 is an enlarged detail view showing the device attached to the razor but removed from the head of the user.

Referring to the drawings in detail:

1 designates the rod portion on one end of 50 which is placed the slidable or extension tube 2 which is designed to engage the upper or rear portion of the ear close to the head as indicated at 3 for positioning this end of the device. Pivottally connected at the point 4 to the opposite end of the rod 1 is a piece 3'. Pivottally attached to this piece is the

part 3'' which is formed with the spaced arms 5 for attaching the device to the safety razor, indicated as a whole by the numeral 6. The space 7 between these arms receives 60 the projections 8 of the razor as shown in Figs. 1 and 5. The handle 8' clamps the piece 3'' in place. 10 designates a spring which passes through an opening 11 in the rod 1. One end of the spring is secured to 65 the rod 1 by means of the slidable piece 12, the other end of the spring is attached to the piece 3' by means of the clamp 3''. The piece 3' is formed with stops to limit the lateral movement of the piece 3'' relative to the 70 piece 3''. The piece 3' is pivotally connected to the piece 3 at the point 13. This pivotal connection is indicated in Fig. 4. Also pivotally connected to the rod 1 at 16 is the 75 piece 14 which is designed to engage the user immediately above the eye as shown in Fig. 1. When the device is used for positioning the razor. The device therefor accurately positions the razor and determines the line on which the hair will be trimmed 80 at the forward portion of the ear. This line is indicated at 15. By sliding the piece 12 along on the rod 1 the angle at which the arm 3' can be opened may be adjusted and varied since this arm would strike the slidable piece and position the edge of the razor.

The dotted lines 18 indicate different angular positions of the member 3'. It is necessary to have the part 14 pivoted since, when the device is used on the opposite side of the 90 head, it must be turned in the opposite direction as shown in Fig. 2. The pivot connection 13 is for permitting the razor to turn in order to bring its cutting edge against the face of the user.

95 It is, of course, understood that the device is only to be used for trimming hair and is then removed after the trimming is completed. The device as constructed may be folded into a compact space and placed in the carrying case of the safety razor.

It is evident that the operator in using the razor moves it upward as indicated by the arrow 17 until the piece 3' strikes the rubber adjusting piece 12 which would determine 105 the upper limit or movement of the razor. It is then drawn downward to produce the accurate trimming of the hair on the line desired.

What I claim is:

110 1. In a device for the purpose described, the combination, of a rod, a sleeve slidably

thereon, a member pivotally connected thereto and having a fork-like extension for attaching the device to a safety razor, and means on the rod for varying and adjusting 5 the extent of movement of the pivoted member.

2. A device for the purpose described, comprising in combination, a rod, an extension member thereon for engaging the 10 upper and rear portion of the ear of the user, a part for engaging the head of the user at or near the eyebrow, a member pivotally connected to the rod for attaching the razor thereto, said member having a 15 pivoted portion to permit the razor to turn, and a part on the rod for varying the extent of movement of the pivoted member.

3. In a shaving gauge, the combination, of a rod, an extension piece thereon, a pivoted member at one end of the rod for positioning the device on the head of the user,

means for attaching the gauge to a razor including a part pivoted to the rod and a second part pivoted to the first part, a spring for holding the first mentioned pivoted member in an inward position and a sleeve slidably on the rod for determining the extent of movement of the first mentioned pivoted member whereby the line at which the hair is to be trimmed may be varied. 25

4. A device for the purpose described, comprising in combination, a rod, parts thereon for engaging the head of the user as at two spaced points, a part connected to the rod for attaching the device to a 30 safety razor, a spring for normally moving the attached razor towards the rod, and means for varying the position of the razor relative to the rod for positioning the razor, whereby the line on which the hair may be 35 trimmed may be varied.

GEORGE POSNICK.
